UNITED STATES PATENT OFFICE.

JOSEPH HOLT LIVINGSTONE, OF WASHINGTON, DISTRICT OF COLUMBIA.

PERMUTATION-LOCK.

SPECIFICATION forming part of Letters Patent No. 660,018, dated October 16, 1900.

Application filed August 15, 1900. Serial No. 26,927. (No model.)

To all whom it may concern:

Be it known that I, JOSEPH HOLT LIVINGSTONE, a citizen of the United States, residing at Washington, in the District of Columbia, 5 have invented certain new and useful Improvements in Permutation-Locks, of which the following is a specification, reference being had therein to the accompanying drawings.

10 This invention relates to permutation-locks, and particularly to a lock of that character embodying rotating tumblers and an automatically-operated throw-off device for placing the tumblers out of combination as 15 and when the door to which the lock is applied is closed.

The invention has for one object to simplify, improve, and economize the construction of locks of this character, and especially the 20 throw-off mechanism for automatically actuating the tumblers and throwing the same out of combination.

A further object of the invention is to improve the construction and arrangement of 25 the supporting-plates for the operating mechanism and also the throw-off slide which engages the tumblers.

Other objects and advantages of the invention will hereinafter appear in the following 30 description, and the novel features thereof will be particularly pointed out in the appended claims.

In the drawings, Figure 1 is an elevation 35 of the face of the lock applied to the door. Fig. 2 is a similar view from the rear with the protecting-casing removed. Fig. 3 is an enlarged horizontal section through Fig. 1. Fig. 4 is a vertical section. Fig. 5 is a top view 40 of the throw-off slide. Fig. 6 is a side elevation of the same. Fig. 7 is a horizontal section of the locking-bolt and its casing, and Fig. 8 is a detail perspective of the tumbler fence-plate and guiding means therefor.

Like letters of reference indicate like parts 45 throughout the several figures of the drawings.

In the drawings the letter A designates a framework of any suitable construction or configuration, within which a pivoted door A' 50 is mounted.

It will be understood that the lock is capable of application to any structure to be

locked; but for the purpose of illustration it has been shown as coöperating with a locking-bolt for the door of a post-office box. The 55 door A' is provided upon its face with suitable apertures for the insertion of the dials B, and the body of the plate about these dials is provided with suitable indicating-points A² for use in connection with the indications 60 B' upon the dial B. This dial is provided with any desired arrangement or number of letters or numerals, preferably of a clearly-defined character, so that the locks may be arranged in a variety of combinations. The 65 dial is provided with a suitable knob B² for rotating the same. This knob is interiorly threaded, as at B³, and provided with an extended shank B⁴, adapted to form a bearing for the same in its rotation.

A suitable front plate C is provided and has a bead C' fitting the aperture in the front plate A'. This plate is also provided with an aperture C², through which the shank B⁴ of the operating-knob passes, and the walls of this 75 aperture provide a bearing for the shank spaced from the bearing-aperture D' of the inner plate D. The inner end of the shank B⁴ of the operating-knob carries a suitable tumbler E, having a gating E', corresponding 80 in position with the letter upon the dial making the proper combination. This tumbler is also provided with a toothed periphery E², by which it coöperates with a throw-off mechanism to be hereinafter described. The tumbler is clamped in position by means of a bolt 85 E³ entering the threaded aperture B³ of the knob B², and a clamping-washer E⁴ is interposed between the head of said screw and the tumbler. A spring friction-washer E⁴ is also 90 interposed between the tumbler E and the back plate D of the lock, thus offering a slight frictional resistance to the rotation of the tumblers.

For the purpose of coöperating with the 95 notches E' in the tumblers E, I have provided a fence-plate F of a very simple and efficient construction. This plate is provided at its upper portion with a cross-head F' and fences F², adapted to sit in the gatings E', while the shank F³ thereof passes through a guide-lug 100 D², bent from the back plate D. This lug has an aperture D³ for the passage of the shank F³ and an additional aperture D⁴ for

the passage of the operating-rod G, carried by the lug F⁴, which is bent outward from the plate F' or otherwise attached thereto. A suitable coiled spring G' surrounds the rod G and rests upon the plate D², so as to be compressed thereon when the fence-plate is forced downward by means of the finger-piece H, located upon the face of the plate A' and connected to the fence-plate F by means of the pin H', operating in a slotted way A³ in the face-plate. It will be seen that the spring G' will restore the fence-plate to an elevated position when pressure is removed from the finger-piece H. The lower end of the rod G bears upon one arm of a crank-lever I, the other arm being in engagement with a slot J', formed in the locking-bolt J. This bolt is mounted at its inner end in a suitable casing A⁴, carried by the plate A', and is projected by means of a spring J², located in the casing A⁴ behind the bolt J. The outer end of the bolt is guided in a slotted case A⁵ and may be retracted by means of a pin J³, carried by the bolt.

25 By means of the foregoing structure the combination of the locking-tumblers may be operated to permit the depression of the rod G and the operation of the locking-bolt J to open the door; but when the door is closed 30 the combination is still in position to permit its being opened again if the operator neglects to turn the knobs B² and throw off the combination. For the purpose of automatically performing this throw-off operation an improved construction of slide K has been provided, which is formed with slotted projections K', adapted to slide over the posts A⁶, extending inward from the face-plate A'. These posts support the throw-off slide K and guide 40 its reciprocations. The slide is also provided with a central offset K², adapted to pass around the lower end of the fence-plate F and permit the free operation of the shank of the same. The slide K is further provided with pivoted 45 pawls or dogs K³, held in an elevated position by any suitable form of spring—such, for instance, as shown at K⁴—so as to normally engage one of the teeth E² upon the periphery of the tumbler. When the door is opened, one end 50 of the throw-off slide next the hinge-side of the door is normally projected beyond the edge of the casing and adapted to engage the door-casing by means of any suitable spring—such, for instance, as shown at L—one end of which 55 is secured to the casing and the opposite end L' adapted to engage one side of the offset K², and thus move the throw-off slide into operative position after the same has been pushed inward by the closing of the door. The closing 60 of the door causes the end K⁵ of the slide to engage the jamb of the casing, thus moving the slide and rotating each of the tumblers E by means of the dogs K³ to such an extent as to move the gatings or recesses E' 65 from beneath the fences F², which throws off the combination and leaves the parts in the position shown in Fig. 2, where the door is in

a locked condition and the tumblers have been reset to open the door.

From the foregoing description the operation of the several parts will be apparent to one skilled in the art, and the structure herein presented is particularly adapted for economical manufacture and efficient operation, as the essential parts can be formed of sheet material and stamped or pressed into shape, while the apertures in and projections from such members as the fence-plate and back plate can be simultaneously cut and require only bending and adjustment when the lock is to be assembled for use. It will likewise be seen that the front plate C is capable of production at a single stamping operation and that all of the parts by reason of their simplicity in construction and operation are not liable to become disarranged in use or broken, whereby the efficiency of the lock is materially increased and the annoyance incident to the disarrangement of complicated structures entirely avoided. The operating parts of the lock are suitably inclosed by a rear casing A⁷, secured by any desired means to the posts A⁶, which project from the face-plate.

It will be obvious that changes may be made in the details of construction and configuration of this invention without departing from the spirit of this invention.

Having described my invention, what I claim as new, and desire to secure by Letters Patent, is—

1. In a permutation-lock, the combination with a tumbler having peripheral teeth and bolt-operating mechanism coöperating with said tumbler, of a throw-off slide having one of its ends normally projecting beyond the lock-casing and adapted to engage the door-casing, a pawl carried by said slide and adapted to engage a tooth on said tumbler, and means for yieldingly projecting said slide in one direction; substantially as specified.

2. In a permutation-lock, the combination with a rotating tumbler provided with peripheral teeth, of bolt-operating mechanism coöperating with said tumbler, a throw-off slide mounted beneath said tumbler and normally projected at one end beyond the lock-casing and adapted to engage the door-casing, a pawl pivotally mounted upon said throw-off slide, and a spring for normally projecting said slide in one direction; substantially as specified.

3. In a permutation-lock, the combination with a face-plate provided with posts extending from its inner face, rotating tumblers supported by said plate and provided with peripheral teeth, bolt-operating mechanism carried by said plate and adapted to coöperate with said tumblers, a throw-off slide provided with slotted ways adapted to rest upon said posts, a pawl carried by said slide and adapted to engage a tooth in said tumblers, and a spring adapted to normally project said slide in one direction beyond the lock-casing where-

by the bolt may be engaged by the door-casing within which said face-plate is pivoted; substantially as specified.

4. In a permutation-lock, the combination 5 with a front plate, of a back plate supported thereby and provided with a lug having a guide-aperture, rotatable tumblers carried by said front plate, a fence-plate having a single shank adapted to pass through the aperture 10 in said lug and coöperating with said tumblers, a pin supported by a lug from said fence-plate and passed through an aperture in the lug upon the back plate, a spring surrounding said pin and resting upon said lugs, and 15 a locking-bolt operatively connected with said pin; substantially as specified.

5. In a permutation-lock, the combination with a front plate, of a back plate supported thereby and provided with a lug having a 20 guide-aperture, rotatable tumblers carried by said front plate, a fence-plate having a single shank adapted to pass through the aperture in said lug and coöperating with said tumblers, a pin supported by a lug from said fence-plate and passed through an aperture in the 25 lug upon the back plate, a spring surrounding said pin and resting upon said lugs, a locking-bolt operatively connected with said pin, a throw-off slide provided with a central off- 30 set portion adapted to bridge the shank of said fence-plate, pawls carried by said throw-off slide and adapted to rotate said tumblers, and a yielding device for projecting one end of said slide beyond the casing thereof where-

by it is adapted to engage the door-casing; 35 substantially as specified.

6. In a permutation-lock, the combination of a door-casing, a supporting-plate pivoted therein, rotating tumblers carried by said plate and provided with toothed peripheries, 40 bolt-operating mechanism coöperating with said tumblers, a throw-off slide supported by said plate and provided with pawls adapted to engage and move said tumblers in the movement of the slide, and a yielding device adapted 45 to normally project one end of the throw-off slide beyond the edge of said supporting-plate whereby the slide may engage the door-casing and be forced inward to rotate the tumblers; substantially as specified. 50

7. In a permutation-lock, the combination with a tumbler and bolt-operating mechanism coöperating therewith, of a throw-off slide having one of its ends normally projecting beyond the edge of a lock-casing and adapted 55 to engage the door-casing, means carried by said slide to operatively engage said tumbler when the slide is moved in one direction and to be inoperative in the return movement of the slide, and means for restoring said slide 60 to its normal position; substantially as specified.

In testimony whereof I affix my signature in presence of two witnesses.
